UNITED STATES PATENT OFFICE.

ALBERT HARRISON DE VOE, OF ELIZABETH, NEW JERSEY, ASSIGNOR TO THE SINGER MANUFACTURING COMPANY, A CORPORATION OF NEW JERSEY.

SEWING-MACHINE PRESSER-FOOT.

SPECIFICATION forming part of Letters Patent No. 793,716, dated July 4, 1905.

Application filed November 29, 1904. Serial No. 234,694.

To all whom it may concern:

Be it known that I, ALBERT HARRISON DE VOE, a citizen of the United States, residing at Elizabeth, in the county of Union and State of New Jersey, have invented certain new and useful Improvements in Sewing-Machine Presser-Feet, of which the following is a specification, reference being had therein to the accompanying drawings.

- This invention relates to an improved sewing-machine presser-foot more especially adapted for use with a lap-seam folder or folder and which is of such construction that in forming lap-seams any danger of displacement of the material in such a manner as to form imperfect seams will be avoided, and more particularly so where thick places occur in the work, as where one lap-seam crosses another. To this end the presser-foot proper has a hinged or pivoted connection with its shank, and rigid with or attached to the latter at one side of the needle-holes in the foot is a guide which is adapted to project down below the bottom of the front portion of the presser-foot in such a manner that when the toe of the pivoted foot is lifted by the passage beneath the same of a thick portion of work the guide will continue to assist in properly directing the work to the needle or needles, so that the goods will not become displaced in such a manner that the infolded edges of the goods will fail to be secured by the lines of stitching.

In the accompanying drawings, Figure 1 is a side view of the improved presser-foot; and Figs. 2, 3, 4, and 5 are plan, front, rear, and bottom views, respectively, of the same. Fig. 6 is a diagrammatic view illustrative of the use of the invention.

Referring to the drawings, *a* denotes a shank adapted for attachment to a presser-bar, and *b* is the presser-foot proper, hinged or pivoted to the front part of the shank *a* by a pin *c*. In the present form of the invention the front or toe portion of the foot *b* is provided with an opening *d*, through which and between the outer sides of said foot extends a guide *e*, preferably formed integral with a right-angled shank *f*, rigidly secured to the presser-foot shank *a* by means of the pivot-pin *c*, passing through the said shank *f*, and the screw *g*, tapped in the presser-foot shank. To provide for a certain limited adjustment of the guide *e* to vary its working position, the said shank *f* is provided with a slot *h*, through which the set-screw *g* passes and which slot when the said screw is loosened permits the position of the guide to be varied, as is desirable for different kinds of work. Thus with thicker goods it is desirable that the guide *e* should project downward somewhat farther beneath the upturned toe portion of the foot *b* than with thin goods, and a proper adjustment to this end can be effected when the set-screw *g* is loosened by turning the guide-shank *f* slightly on the pivot-pin *c*. A coil-spring *i*, housed in the shank *a* and pressing on the upper surface of the presser-foot *b* rearward of the pivot-pin *c*, has a tendency to lift the front or toe portion of the said foot, so that the goods will readily enter beneath the latter, and particularly so when thick portions of work or cross-seams have to pass beneath the presser-foot, the said spring yielding when the cross-seams or thick portions of the work pass beneath the heel portion of the foot, thereby permitting the inequalities of the work to run smoothly through the machine. The upturned toe portion of the foot is preferably inclined away from the said guide *e* and in a plane transverse to the said foot or to the feed of the work, this inclination being preferably carried down to the bottom portion of the foot, as more clearly shown in Fig. 5. The guide *e* is also preferably chamfered or rounded off in front on its inner side. Owing to these constructions the lap-seam folder may be set well toward the left, Fig. 3, and the folded material passing the right-hand edge of the guide will be ironed or smoothed down by the inclined toe portion of the presser-foot in such a manner that the folded goods forming the seam will be laid smooth and flat as they are presented to the needles of the machine and the positions of which needles are indicated by the needle-

holes *h* in the presser-foot *b*. This desirable result is due to the fact that owing to the inclined toe portion of the presser-foot extending down to the bottom portion of said foot 5 the part of said foot which is adjacent to the edge-guide *e* will engage the top of the entering material first, and any extra fullness of material will yield or escape toward the right-hand edge of said foot, Fig. 6, and the 10 entering material will thus be ironed down smooth, as above stated, and particularly so in stitching around curves when there is sometimes more fullness or surplus material.

The relative positions of the folded goods, 15 the guide, and the presser-foot are somewhat diagrammatically illustrated in Fig. 6, and from which and the foregoing description the operation of the invention will be readily understood by those skilled in the art and in 20 which the vertical lines *m* indicate, approximately, the positions of the needles in the sewing operation.

Owing to the fact that the pivot-pin *c* of the foot-piece *b* is intermediate the ends of 25 said foot-piece, the rise of the presser-foot shank *a* and of the guide *e* rigid therewith when cross-seams or other thick parts of the work pass beneath the presser-foot is about equal to the mean rise of the opposite ends 30 of the foot-piece or about one-half of the rise of the toe portion of the said foot-piece, so that the said guide will always maintain such a proper relation to the bottom of the foot-piece as will prevent lateral displacement of 35 the work at all times.

Having thus described my invention, I claim and desire to secure by Letters Patent—

1. A sewing-machine presser-foot comprising a shank, a foot portion pivoted thereto, 40 and an edge-guide rigid with said shank and extending downward beneath the upturned toe portion of the said pivoted presser-foot between the outer sides of the latter.

2. A sewing-machine presser-foot comprising a shank, a foot portion pivoted thereto, 45 and a guide rigid with said shank and extending downward beneath the upturned toe portion of the presser-foot, said guide being adjustably connected with said shank so that its 50 working position may be varied.

3. A sewing-machine presser-foot comprising

ing a shank, a foot portion pivoted thereto, a guide rigid with said shank and extending downward beneath the upturned toe portion of the said pivoted presser-foot between the outer sides thereof, and a spring bearing against said foot portion rearward of its pivot, so as to have a tendency to lift the said toe portion. 55

4. A sewing-machine presser-foot comprising a shank, a foot portion pivoted thereto, and an edge-guide rigid with said shank and extending downward beneath the upturned toe portion of the said pivoted presser-foot between the outer sides thereof, said toe portion being inclined, transversely of said foot, away from said guide. 60

5. A sewing-machine presser-foot comprising the shank *a*, the foot *b* pivoted thereto, the guide *e* extending through and beneath 70 the upturned toe portion of said foot and the right-angular shank *f* carrying the said guide *e* and rigidly attached to the said shank *a*.

6. A sewing-machine presser-foot comprising the shank *a*, the foot *b* pivoted thereto, 75 the guide *e* extending beneath the upturned toe portion of said foot and the right-angular shank *f* carrying the said guide *e* and rigidly attached to the said shank *a*, said shank *f* having a slot *h* to permit its working position to 80 be varied, and through which slot the set-screw *g* passes.

7. A sewing-machine presser-foot comprising a shank, a foot-piece pivoted to said shank at a point intermediate the ends of said foot-piece, and a guide rigid with said shank and extending through and beneath the upturned toe portion of said pivoted foot-piece. 85

8. A sewing-machine presser-foot comprising a shank, a foot-piece pivoted to said shank 90 at a point intermediate the ends of said foot-piece, and a guide rigid with said shank and extending beneath the upturned toe portion of said foot-piece, said guide being adjustably connected with said shank so that its working 95 position may be varied.

In testimony whereof I affix my signature in presence of two witnesses.

ALBERT HARRISON DE VOE.
